UNITED STATES PATENT OFFICE.

JACOB BUCKMAN, OF NEW YORK, N. Y.

HOOD.

1,167,379.

Specification of Letters Patent. Patented Jan. 11, 1916.

Application filed January 30, 1915. Serial No. 5,298.

To all whom it may concern:

Be it known that I, JACOB BUCKMAN, a citizen of the United States, residing at New York, in the county and State of New York, have invented certain new and useful Improvements in Hoods, of which the following is a full, clear, and exact specification.

This invention relates to hoods for covering the head, and has for its object to produce a hood, of improved construction, a portion of which is adapted to form a collar for a garment and to be folded back in a very smooth and compact form when not in use over the head of the wearer.

Another object is to provide a hood, a part of which forms a collar having the smooth folding feature, and which is also provided with means for covering a pair of goggles for retaining the latter in place and further protecting the face of the wearer as when riding in an automobile.

Still another object is to provide a foldable hood, a part of which forms a collar, and which is provided with a visor having means for securing the latter in folded position when not in use.

Other objects will appear as the description proceeds.

The invention will be first hereinafter described in connection with the accompanying drawings, which constitute a part of this specification, and then more specifically defined in the claims at the end of the description.

In the accompanying drawings, wherein similar reference characters are used to designate corresponding parts throughout the several views:—Figure 1 is a rear view of one form of hood constructed in accordance with this invention, showing how it may be folded into smooth compact form so as to resemble a sailor collar, when not in use as a head covering. Fig. 2 is a front view of the same hood as it appears when used to cover the head. Fig. 3 is a front view of another form of hood having a visor like a golf cap and equipped with foldable flaps or coverings for the face or a pair of goggles.

Fig. 4 is a rear view of the hood illustrated in Fig. 3, showing how it looks when folded back. Fig. 5 is a detail view of the face coverings or flaps. Fig. 6 is a front view of still another style of hood as it appears when worn on the head. Fig. 7 is a rear view of the same, and Fig. 8 is a rear view of

the last style of hood, showing how it appears when folded.

Referring first to Figs. 1 and 2, 1 designates a hood which is made generally in the shape of a sailor collar but of double thickness of material so that it may be opened, as shown in Fig. 2, to form a covering for the head. The corner portions 2 of the hood when folded back like a sailor collar, are turned down on a transverse fold, as illustrated in Fig. 2, when the hood is placed on the head. These corner portions may be provided with supplemental snap fasteners 3 and 4 for securing them in the position shown in Fig. 2, so that they will retain the hood in proper shape while it is being worn on the head and will give a very pleasing appearance. Part of the hood 1 forms the collar 6 of the coat, and is permanently attached to the latter as at 7. The collar is provided with forward extensions to be secured under the chin of the wearer, as at 8, thereby holding the front edge of the hood closely around the face, said forward edge of the hood being slightly gathered, as at 5, to further this result.

As illustrated in Figs. 3 and 4, the hood 9 there shown is of the golf cap type having a visor 10. Forward extensions 11 are adapted to be secured under the chin for retaining the hood in proper position on the head. When folded back, as shown in Fig. 4, the visor 10 may be held down flat by means of a snap fastener 12.

Flaps or coverings 13 for the face are illustrated in connection with the hood 9, but it will be understood that they may be used on any of the other types of hoods illustrated and described herein. These flaps 13 have openings 14 for the eyes to look through, and are provided with tabs 15 stitched or otherwise secured to the side portions of the front edge of the hood. Said flaps are also provided with tabs 16 at their free ends to be detachably connected together by snap fasteners or the like for holding them in position when worn. Upwardly projecting tabs 17 extend up under the visor and help to retain said flaps in position. When not in use, the flaps 13 may be unbuttoned at 16 and rebuttoned at the sides of the hood where they will be securely held.

Figs. 6, 7 and 8 illustrate another style of foldable hood shaped like a stocking cap. This hood 18 has its front edge slightly gathered with elastic, as at 19, to hold it

close around the face, and is also provided with front extensions 20 to be fastened together under the chin. When this hood is folded back, as illustrated in Fig. 8, it gives 5 a very neat appearance resembling a collar of novel shape.

While I have shown the hood connected to a garment with a part thereof forming a permanent collar, said hood may also be 10 made and worn as a detachable hood and collar.

It will be understood that any form or type of hood may be made either as a permanent part of a garment, or as a separate 15 piece to be detachably connected to a coat collar or coat.

It will also be understood that in either case, my combined collar and hood does not mar the set of the lapels or the appearance 20 of the coat when viewed from the front, when the hood is in a folded position either inside or outside of the coat.

Having thus described my invention, what I claim as new and desire to secure by Letters Patent of the United States is:—

1. A hood made of double thickness of material to lie flat in the form of a sailor collar when folded and not in use, and to be opened for covering the head, and separable 30 fastening means for retaining the corner portions of the folded hood in transverse turned down folds when used as a covering for the head.

2. A hood made of double thickness of material to lie flat in the form of a sailor collar when folded and not in use, and to be opened for covering the head, separable fastening means for retaining the corner portions of the folded hood in transverse turned 40 down folds when used as a head covering, forward extensions on the hood, and separable fastening means on said extensions for

connecting them below the chin of the wearer.

3. The combination with a foldable hood, 45 of flaps permanently secured to the side portions of the front edge of the hood and having separable fastening means on their free ends for securing said free ends together for protecting the face of the wearer. 50

4. The combination with a foldable hood, of flaps permanently secured to the side portions of the front edge of the hood each flap having an eye space, and means for fastening the free ends of the flaps together for the 55 purpose specified.

5. The combination with a foldable hood, of flaps secured to the side portions of the front edge of the hood and having upwardly extending tabs to extend up and be held 60 below the top portion of said front edge of the hood, and means for fastening the free ends of the flaps together over the nose of the wearer.

6. A foldable hood having a visor, and 65 separable fastening means near the edge of the visor and on the body of the hood for holding said visor flat upon the hood when the latter is folded.

7. The combination with a foldable hood 70 having a visor, of flaps secured to the side portions of the front edge of the hood and having eye spaces, said flaps also having upwardly projecting tabs reaching up below the visor, and means for fastening the free 75 ends of the flaps over the nose of the wearer.

In testimony whereof I have signed my name to this specification in the presence of two attesting witnesses.

JACOB BUCKMAN.
